United States Patent

Des. 236,546
Patented Aug. 26, 1975

236,546

CAMERA HOUSING

Moto Shimano and Walter Nakano, Los Angeles, Calif.,
assignors to Optigon Research & Development Corporation, Santa Monica, Calif.

Filed Nov. 28, 1973, Ser. No. 419,591

Term of patent 14 years

Int. Cl. D16—01

U.S. Cl. D61—1 B

FIG. 1 is a top, left, front perspective view of a camera housing showing our new design;

FIG. 2 is a bottom plan view thereof;

FIG. 3 is a rear elevational view thereof;

FIG. 4 is a right side elevational view thereof;

FIG. 5 is a left side elevational view thereof.

We claim:

The ornamental design for a camera housing, as shown.
